UNITED STATES PATENT OFFICE.

PHILIP N. BRAUN, OF SYRACUSE, NEW YORK, ASSIGNOR TO THE PROSPERITY COMPANY INC., OF SYRACUSE, NEW YORK, A CORPORATION OF NEW YORK.

VALVE MECHANISM FOR PRESSING MACHINES.

Application filed September 27, 1927. Serial No. 222,370.

This invention relates to pressing machines as garment pressing machines having a valve for controlling the flow of fluid as steam or air through the pressing face and has for its object a particularly simple and efficient handle arrangement for bringing the head toward the buck of the machine and also operating, when desired, the valve which controls the flow of fluid through the pressing face of the head.

The invention consists in the novel features and in the combinations and constructions hereinafter set forth and claimed.

In describing this invention, reference is had to the accompanying drawing in which like characters designate corresponding parts in all the views.

Figure 1 is a fragmentary plan view of a machine embodying my invention.

Figure 2 is a fragmentary side elevation.

Figure 3 is a detail view of the mounting for the handle.

I have here illustrated my invention as embodied in a conventional type of pressing machine including a buck 1 and a head 2 movable toward and from the buck; the buck being mounted on a goose neck or bracket 3 which in turn is mounted upon a bench 4 carried by the frame 5 of the machine and the head 2 being carried in any suitable manner to move toward and from the buck.

As here shown, it is carried by a yoke lever 6 pivoted between its ends at 7 to a standard 8 rising from the machine, this yoke being actuated in any well known manner by means connected to the rear arm thereof, a portion of such means as one link 9 of a toggle being shown.

The yoke is provided with a suitable counterweight 10 tending to open the press and also usually springs, not shown, are employed to act in conjunction with the weight 10.

The head 2 as will be understood by those skilled in the art is provided with perforations through its pressing face through which steam or air is passed to the garment being pressed. As the steaming of garments in this manner and the blowing or sucking of air through the garments is well known, further description is unnecessary for a complete understanding of this invention. The flow of the fluid is controlled by a nor-

mally controlled valve operated at will by the operator.

11 designates the valve which includes a movable member located within the casing thereof, which member is operated by a movable operating member as the stem 12 extending to the outside of the casing.

13 designates a handle mounted on the head to move the same toward the buck preliminary to applying final pressure, the handle being movable in a direction at an angle 65 to the movement of the head into engagement with the valve operating member 12 to actuate it.

As here shown, the handle is a lever pivoted on an upwardly extending axis to the 70 head so that the lever is rigid with the head insofar as the up and down movement of the head is concerned, the lever being movable laterally about its pivot in a direction at an angle to the movement of the head to 75 move an arm 14 thereof into engagement with the stem 12.

The pivot pin 15 of the lever is inclined laterally out of the vertical away from the valve stem 12 so that the lever tends to some 80 extent to resist lateral movement and hence, an intended effort must be made to move it laterally to operate the valve stem 12. Also owing to the inclination of the pivot pin 15, the lever tends to return to its normal 85 position when released.

As here illustrated, a bracket 16 is mounted on the top of the buck and is formed with upper and lower arms 17 and 18 in which the inclined pivot pin 15 is mounted. If desired, a spring may be used to resist the lateral movement of the lever.

This handle mechanism is particularly advantageous in that it acts, without conscious effort, rigidly with the head to close 95 the press and operates the valve stem upon a slight conscious lateral movement.

What I claim is:

1. A pressing machine comprising a buck, a head movable toward and from the buck, 100 a valve mounted on the head for controlling the flow of the fluid through the pressing face of the head, the valve including a movable operating member and a handle carried by the head for moving the same 105 toward the buck and also movable laterally relatively to the direction of movement of the head and having means for actuating said

valve operating member during the lateral movement.

2. A pressing machine comprising a buck, a head movable toward and from the buck, a valve mounted on the head for controlling the flow of fluid through the pressing face of the head, the valve including a movable operating member and a handle lever carried by the head and pivoted thereto on an upwardly extending pivot and having an arm movable into engagement with the valve operating member during the pivotal movement of the lever.

3. A pressing machine comprising a buck, a head, movable toward and from the buck, a valve mounted on the head for controlling the flow of fluid through the pressing face of the head, the valve including a movable operating member and a handle lever carried by the head and pivoted thereto on an upwardly extending pivot and having an arm movable into engagement with the valve operating member upon pivotal movement of the lever, said pivot being inclined out

of the vertical in such direction as to tend 25 to move the lever away from the valve operating member.

4. A pressing machine comprising a buck, a head movable toward and from the buck, a valve mounted on the head for controlling 30 the flow of a fluid through the pressing face of the head, the valve including a movable operating member, a handle carried by the head for moving the same toward the buck and also movable laterally relatively to the 35 direction of movement of the head and having means for actuating said valve operating member during the lateral movement, the handle being mounted to resist lateral movement out of its normal position and to return 40 towards its normal position from its laterally shifted position.

In testimony whereof, I have hereunto signed my name at Syracuse, in the county of Onondaga, and State of New York, this 45 24th day of September, 1927.

PHILIP N. BRAUN.
